(57) **CLAIM**

The ornamental design for a drum practice pad, as shown and described.

DESCRIPTION

FIG. 1 is a front elevational view of a drum practice pad showing my new design;

FIG. 2 is a top plan view thereof;

FIG. 3 is a bottom plan view thereof;

FIG. 4 is a perspective view thereof; and,

FIG. 5 is a bottom plan view thereof; shown at an enlarged scale.

The broken lines shown in the drawing are for illustrative purposes only and form no part of the claimed design.
